HOLDER FOR COCKTAIL OLIVES AND THE LIKE

James H. Ogg, North Hollywood, Calif., assignor to Zoo-Piks, North Hollywood, Calif., a partnership

Filed Apr. 9, 1963, Ser. No. 74,361

Term of patent 14 years

(Cl. D44—29)

FIG. 1

FIG. 2

FIG. 3

FIG. 4

I claim:

The ornamental design for a holder for cocktail olives and the like, substantially as shown.
